UNITED STATES PATENT OFFICE

144,378

DESIGN FOR A BUILDING SIDING PANEL OR THE LIKE

Myer J. Harris, Richmond, Va.

Application July 23, 1945, Serial No. 120,914

Term of patent 7 years

(Cl. D68—1)

To all whom it may concern:

Be it known that I, Myer J. Harris, a citizen of the United States, residing at Richmond, in the State of Virginia, have invented a new, original, and ornamental Design for a Building Siding Panel or the like, of which the following is a specification, reference being had to the accompanying drawing, forming a part thereof.

Figure I is a front elevational view of a building siding panel or the like showing my new

design; and Figure II is a cross section of a part of the panel taken on line *a—b* in Figure I.

The essential features of my design reside in the curved ridges shown in relief on the surface of the panel.

I claim:

The ornamental design for a building siding panel or the like, substantially as shown and described.

MYER J. HARRIS.
